UNITED STATES PATENT OFFICE.

MATHIAS PAQUETTE, OF CARNEY, MICHIGAN.

PROJECTILE.

1,276,400.

Specification of Letters Patent. Patented Aug. 20, 1918.

Application filed July 10, 1917. Serial No. 179,739.

To all whom it may concern:

Be it known that I, MATHIAS PAQUETTE, a citizen of the United States, residing at Carney, in the county of Menominee and 5 State of Michigan, have invented new and useful Improvements in Projectiles, of which the following is a specification.

This invention relates to projectiles and more particularly to that form of projectile 10 designed to emit fumes or gases upon explosion of the charge carried by the shell.

The object is to provide in a device of the character indicated an improved construction which shall render the missile more efficient in operation than those heretofore employed.

A further object is to provide certain means of novel construction for firing the charge.

20 With these and other objects in view, the invention consists in the novel construction, combination and arrangement of elements hereinafter described and claimed.

In the drawings:

25 Figure 1 is a view of the projectile in longitudinal section.

Fig. 2 is a transverse section on line 2—2 of Fig. 1.

30 Fig. 3 is a longitudinal section of another form of the device.

Fig. 4 is an end view of the form shown in Fig. 3.

In carrying out my invention I employ a casing 10 provided with a head 12, said head being cut away as indicated at 14 and threaded for engagement with the internally threaded portion of the flange 15 of the body portion of the shell. The projectile proper is made of steel and the nose portion 18 35 formed of softer metal such as lead which will permit the nose to collapse under impact and cause the operation of the firing pin 20 mounted within a bore 21 in said nose portion and extending through a bore 40 45 22 in the head proper. A recess is provided at 23 at a point opposite the cap 24, this cap being located at the end of the central bore or channel 25 in which the main charge is placed.

50 Communicating with the central longitudinal channel 25 are a plurality of bores or chambers 28 extending radially and terminating at the surface of the shell, any suitable number being employed. These chambers 55 28 are filled with chloroform or other suitable material and are closed at opposite

ends by means of wadding designated 29 and 30. The additional chambers or channels 31 communicate with bore 25 and extend toward the butt end of the shell terminating at the points 32. These channels diverge with reference to each other and are intended to discharge their contents in a direction approximately opposite to the direction in which the projectile is traveling. In the event that the shell strikes a wooden structure or target of any character and penetrates to a given distance before exploding, these rearwardly extending channels will discharge their contents, 70 whereas those extending radially from the bore may be obstructed owing to the entrance of the shell into the structure of the target, whatever the latter may be.

In the form shown in Fig. 3 the same 75 principle is carried out, but the chambers for receiving explosive material and the chloroform or other similar substance are differently located. The body portion of the projectile is designated 35 and is formed of 80 steel as is also the head 36, the nose portion 37 being of softer material as in the previous instance, lead being usually employed for this purpose.

The firing pin is designated 38 and extends through a bore 39 in the nose portion 37 and through a registering bore 40 in the head proper. The head is provided with a recess formed by making the inner portion thereof concave as shown at 41 and the 90 firing pin projects beyond the wall of this recess into position for engagement with the cap 42 mounted at the end of the magazine 43 carrying the explosive charge. This magazine may comprise a channel or series 95 of channels extending around the core 45 of the projectile and in a longitudinal direction. Another channel or series of channels 44 concentric with channels 43 are adapted for the reception of chloroform or 100 other similar material.

The head is connected with the body portion by means of a flanged member 47 co-operating with an annular threaded channel 48, whereby the elements are firmly secured. 105

It will be observed that in the second form above described the openings extending from the chambers formed within the shell are toward the rear and these openings are suitably closed as by means of devices 50 and 51. 110

What is claimed is:

1. In a projectile, a body portion provided

- with a channel extending longitudinally thereof, a head having connection with said body portion and provided with a collapsible nose piece, a firing pin positioned within 5 said head and operative upon the collapse of the nose piece, and receptacles for containing material adapted to emit fumes upon the explosion of a charge, said head having a concave end portion and the nose piece 10 having a convex end portion coöperating with the concave portion and having a bore flared toward its outer end, said firing pin being rounded at its end conforming to the curvature of the collapsible nose piece, and 15 being tapered to conform to the flared bore.
2. In a projectile, a body portion provided with a series of channels extending longitudinally and located around the main axis of the projectile, said body portion including 20 a central bore within said series of channels, a second series of channels concentric with that first named and adapted to contain material emitting fumes upon the explosion of a charge within the channels first 25 named, said channels first named converging
- toward one end adjacent the head, and a cap located between said converging portions and opposite the end of the core, a head and a nose piece for said projectile, and a firing pin extending through said head and 30 nose piece to a point adjacent the cap.
3. In a projectile, a body portion provided with a plurality of concentrically arranged and longitudinally extending channels, certain of the channels being adapted to contain 35 an explosive charge and others to contain material emitting fumes upon the explosion of the charge, the body portion including a central bore of reduced diameter at its forward end, and the inner series of channels 40 converging toward said reduced portion of the core and extending beyond said reduced portion providing a recess for receiving a cap, a head, and a nose portion connected with the body portion, a firing pin extending 45 through said head and nose portion to a point adjacent a cap located within said recess.

In testimony whereof I affix my signature.
MATHIAS PAQUETTE.
